OF MAINE.

ART OF CRACKING HYDROCARBON OILS.

Application filed August 12, 1927. Serial No. 212,482.

This invention relates to improvements in the cracking of heavier and higher boiling hydrocarbon oils, such as gas oil, to produce therefrom lighter and lower boiling hydrocarbon oils, such as gasoline and gaso-line-containing pressure distillates. The invention includes an improved method of cracking hydrocarbon oils, improved features of operation, and an improved apparatus.

In carrying out the present invention, a body of oil is maintained in a vaporizing zone under a superatmospheric pressure and at a cracking temperature and vapors including vapors of the cracked product are taken off from this vaporizing zone under pressure. Oil is forced into this vaporizing zone through heating tubes in which it is heated to a cracking temperature. The oil forced through these heating tubes may be a mixture of raw oil and reflux condensate refluxed from the vapors taken off from the vaporizing zone, and it may also include oil recirculated through these heating tubes from the vaporizing zone. Residual oil is discharged from this first vaporizing zone into a separate vaporizing zone maintained under a pressure lower than that prevailing in the first, and the vapors separated under this lower pressure are taken off and subjected to a condensing operation. This condensing operation may be a fractionating operation through which lighter components of the vapors are permitted to pass uncondensed. Condensate from the condensing operation to which the vapors from the second vaporizing zone are subjected is then forced through separate heating tubes into the first vaporizing zone. The heating gases for supplying heat to the cracking operation are passed first over these separate heating tubes through which condensate from the condensing operation to which the vapors from the second vaporizing zone are subjected is passed and then over the first mentioned heating tubes. The heating tubes through which the condensate from the vapors separated from the residual oil in the second vaporizing zone is circulated are thus exposed to the heating gases while at highest temperature and the heating gases contact with the remaining heating tubes through which raw oil and reflux condensate from the first vaporizing zone and any oil

recirculated from the first vaporizing zone are passed only after reduction in temperature due to heat absorption by the heating tubes with which the heating gases first contact.

The second vaporizing zone is advantageously externally unheated and the vaporization therein effected by the self-contained heat of the residual oil on reduction of pressure. The vaporization in the second vaporizing zone may be carried so far that the unvaporized residue remaining is of coke-like character or it may be restricted so that the unvaporized residue can be discharged from the second vaporizing zone as a fluid pitch or tar. The vaporization in the second vaporizing zone can be controlled by regulating the pressure therein. Where the vaporization is carried to a point such that the unvaporized residue remaining is of a coke-like character, a plurality of separating vessels are provided to avoid interference with continuity of operation. The first vaporizing zone also is advantageously externally unheated.

In addition to the desired lighter and lower boiling hydrocarbon oils, the products of the cracking operation include heavy asphaltic and pitch-like constituents which tend to form deposits on the heating surfaces of cracking stills with consequent danger of overheating the surfaces on which such deposits occur. This effect is cumulative. Usually, the formation of such carbonaceous deposits is the limiting factor in determining the useful period of operation as they necessitate periodic shut down for cleaning. These asphaltic and pitch-like constituents are formed progressively as the cracking operation continues, and unless they exceed the saturation point they may be largely maintained in solution in the charge of oil in the cracking still. The useful period of operation of the cracking still can be materially prolonged, as described in Letters Patent No. 1,598,136 issued to the Sinclair Refining Company, August 31, 1926, by appropriately regulating the supply of fresh oil to and the discharge of pitch-laden oil from the charge of oil in the cracking still. This method of operation, however, requires the discharge from the pressure still of a large amount of residual pitch-laden oil and this residual oil also includes a substantial proportion, fre-

quently a predominating proportion, of oil constituents suitable for further cracking to produce further quantities of the desired lighter and lower boiling hydrocarbon oils.

5 In carrying out the present invention, the concentration of asphaltic and pitch-like constituents in the body of oil in the first vaporizing zone may be kept below an objectionable value or below saturation as described 10 in said Letters Patent No. 1,598,136, and the oil constituents suitable for further cracking of the residual oil discharged from the first vaporizing zone returned to the cracking operation in a particularly advantageous manner. The asphaltic or pitch-like constituents 15 of the residual oil are separated in the second vaporizing zone, and the oil constituents vaporized to a greater or less extent from this residual oil in the second vaporizing zone are condensed and returned to the first vaporizing zone after again being heated to a cracking temperature. The return of oil constituents discharged from the first vaporizing zone with the residual oil may thus be 20 effected with very little heat loss. Likewise, in carrying out the invention, these returned oil constituents which are somewhat refractory to further cracking are subjected to relatively severe and advantageous cracking 25 conditions and are also employed to assist in protecting the heating tubes through which raw oil and reflux condensate and any recirculated unvaporized oil are discharged into the first vaporizing zone.

30 35 In carrying out the invention, the vapors from the first vaporizing zone are subjected to a refluxing operation from which reflux condensate is returned to the first vaporizing zone through the first mentioned heating 40 tubes. Raw oil may be supplied to the stream of reflux condensate flowing back to these heating tubes, or the raw oil supplied to the operation, or part of it, may be introduced into the vapors in the refluxing 45 operation for preheating the raw oil and refluxing the vapors. This refluxing operation, for example, is advantageously controlled by the regulated introduction of raw oil in this manner. Additional raw oil may 50 then be supplied to the stream of reflux condensate and admixed raw oil flowing through these heating tubes. This refluxing operation, however, may be effected and controlled by other cooling means. The condensing operation to which the vapors from the second 55 vaporizing zone are subjected may be a refluxing or fractionating operation, and this operation also may be controlled by regulated introduction of a part of the raw oil 60 supplied to the operation. This refluxing or fractionating operation, however, may with advantage be effected or controlled by return and reintroduction into the vapors in this refluxing or fractionating operation of 65 a part of the distillate product, either from

the refluxing operation to which the vapors from the first vaporizing zone are subjected or from the refluxing operation to which the vapors from the second vaporizing zone are subjected or from both. This second refluxing or fractionating operation also may be effected or controlled by other cooling means. 70 The invention is of special value and application in connection with pressure cracking stills of the general type described in 75 Letters Patent No. 1,285,200 issued to the Sinclair Refining Company, November 19, 1918, and it will be further described more particularly in connection therewith. The pressure still system illustrated in the accompanying drawings is of the general type described in said Letters Patent No. 1,285,200, and includes in addition an auxiliary bank of heating tubes arranged in the path 80 of the heating gasses between the firebox and the heating tubes of the pressure still proper, as described in application Serial No. 664,502 filed September 24, 1923. In certain aspects, however, the invention has advantages which 85 are of more general application. 90

The invention will be further described in connection with the accompanying drawings which illustrate, in a diagrammatic and conventional manner, in elevation and partly in section and with parts broken away, a pressure still system embodying the invention and adapted for the practice of the invention. 95

Referring to the drawings, the pressure still system illustrated comprises a bulk supply drum 1, a battery of heating tubes 2 arranged in the heating flue of a furnace 3 and circulating connections 4, 5 and 6 including a circulating pump 7 arranged to provide for circulation of oil from the bulk supply drum 1 upwardly through the heating tubes 2 and back to the bulk supply drum. An auxiliary bank of heating tubes 8 is arranged in the furnace in the path of the heating gasses between the firebox 8 and the heating tubes 2. Before passing over the heating tubes 2, heating gasses including fresh hot products of combustion from the firebox 9 are thus tempered by heat absorbed in the separate bank of heating tubes 8. Further to assist in tempering the heating gasses, a portion of the waste heating gasses about to escape through the stack flue 10 may be returned and admixed with the fresh hot products of combustion from the firebox through the return flue 11, provided with suitable forcing means such as a steam jet or fan. The auxiliary bank of heating tubes 8 is arranged to discharge into the bulk supply drum 1 through connection 12 and the return circulating connection 6. 110 115 120

Vapors from the bulk supply drum 1 escape through connection 13 and pass upwardly through the reflux tower 14, uncondensed vapors escaping from the upper end 130

of this reflux tower through connection 15 to the condenser 16 arranged to discharge into the receiver 17. A connection 18 is provided for the discharge of the distillate product and a connection 19 for the discharge of uncondensed vapors and gases from this receiver. Raw oil may be introduced into the upper end of the reflux tower 14 through connection 20. Reflux condensate, and any admixed unvaporized raw oil introduced into this reflux tower, are returned from the reflux tower 14 through connection 21 to the circulating connection 4 connecting the bulk supply drum with the suction side of the circulating pump 7.

Unvaporized residual oil is discharged from the bulk supply drum 1 through connection 22 into the separator 23. A pressure reducing valve 24 is provided in connection 22, advantageously at a point adjacent the bulk supply drum, to control and reduce the pressure between the bulk supply drum 1 and the separator 23. To promote vaporization, steam, or other heated gaseous medium, may be introduced into the separator 23. For example, steam may be injected into and admixed with the residual oil from the bulk supply drum as it enters the separator. As little as 1% of steam will, in many cases, materially increase the amount of vaporization over any particular pressure drop. To inhibit entrainment, several baffles or other suitable means may be arranged in the upper end of the separator 23.

Connection 25 is provided for the discharge, for example through suitable cooling means, of fluid residues from the separator 23. Vapors escape from the separator 23 through connection 26 to a point somewhat above the lower end of the reflux tower 27. Vapors escaping uncondensed from the upper end of reflux tower 27 pass through connection 28 to condenser 29 arranged to discharge into receiver 30. Connection 31 is provided for the discharge of condensate and connection 32 for the discharge of uncondensed vapors and gases from this receiver. To effect or control condensation in the tower 27, a part of the condensate from either or both of the receivers 17 and 30, or a light oil of similar character, may be introduced into the upper end of this tower through connection 33.

Condensate collecting in the lower end of the reflux tower 27 is forced by means of pump 34 through the auxiliary bank of heating tubes 8 and thence into the bulk supply drum 1. Condensate from the tower 27 passes to the pump through connection 35 and is discharged from the pump into the heating tubes 8 through connection 36. Additional oil may be supplied to the heating tubes 8 through connection 37, and a part of the reflux condensate from tower 27 may be discharged through connection 38, as re-

quired. It is advantageous to provide suitable storage space for hot reflux condensate from the tower 27, for example in the lower end of tower 27, to promote uniformity of operation.

The pressure in the bulk supply drum 1 may be maintained and regulated by valve 39 in the vapor connection between the reflux tower 14 and the condenser 16, or by suitable valves arranged beyond the condenser or receiver. Cool oil for cooling and lubricating the bearings of the circulating pump 7 may be supplied through connection 40, or an amount of raw oil in excess of that required for cooling and lubricating the circulating pump bearings may be introduced into the circulating oil through this connection. Connection 41 is provided for pumping out the still at the end of a run and for initially charging the still at the beginning of a run. Connection 42 is provided for draining the auxiliary bank of heating tubes 8. Suitable valves, 43 and 44, for example, are provided whereby the pressure in the separator 23 may be regulated and controlled. The hot parts of the apparatus, including the bulk supply drum 1 and the vapor separating chamber 23 as well as the various hot connections, are advantageously lagged or heat insulated to prevent heat loss. In particular, the vapor separating chamber 23 is advantageously heavily lagged or heat insulated. To promote condensation, the reflux tower 27 may be left uninsulated, although control is somewhat facilitated if this tower is also insulated against heat loss.

In carrying out the invention in the apparatus illustrated, a body of oil is maintained under a superatmospheric pressure and at a cracking temperature in the bulk supply drum 1 of high pressure vaporizing zone and vapors are taken off from this vaporizing zone under pressure, oil from this body is circulated through the heating tubes 2 in which it is heated to a cracking temperature and back to the body, residual oil is discharged from this body into the separator 23 or second vaporizing zone in which vapors are taken off under reduced pressure, these vapors are subjected to a condensing operation in the reflux tower 27 and the condensate from this condensing operation is forced through the separate heating tubes 8 into the bulk supply drum 1 or first vaporizing zone, and the heating gases from the fire box 9, in which fuel is burned for supplying heat to the cracking operation, are passed first over the heating tubes 8 and then over the heating tubes 2. Reflux condensate from reflux tower 14, together with any admixed unvaporized raw oil introduced through connection 20, is returned to the body of oil circulating through the heating tubes 2 through connection 21.

In operation, the pressure still is charged

with raw oil and the charge is gradually brought to cracking conditions of temperature and pressure in the usual way. In a still of the type illustrated, an initial charge of about 8,000 gallons of cold oil, that is oil at a temperature of about 80° F. for example, is commonly used. During the initial period of operation, or until an adequate supply of condensate from tower 27 is available, oil may be circulated through the heating tubes 8 from the discharge side of the circulating pump 7 by means of the by-pass connection 45, or raw oil may be pumped into the still through these heating tubes by means of pump 34 during this period of operation. The pressure maintained on the bulk supply drum 1 during operation is determined to a large measure by the stocks to be treated and the products to be obtained. With gas oil character charging stocks, and for the production of gasoline, pressures up to 125 pounds per square inch or more may be used and with charging stocks containing large amounts of kerosene character components much higher pressures, say up to 300 pounds per square inch or more, may be used. When the still is brought to operating conditions, the introduction of raw oil through connection 20 is begun, and the supply of raw oil through this connection is regulated to condense in the reflux tower 14 those components of the vapors heavier or higher boiling than desirable as components of the distillate product. The discharge of unvaporized oil from the still may be omitted during the initial period of operation or may be in but small amount, but before the concentration of pitch-like constituents in the charge of oil in the pressure still reaches an objectionable value, the withdrawal of pitch-laden oil in substantial amount is begun and the rate of withdrawal of pitch-laden oil and the supply of raw oil is regulated to maintain the concentration of pitch in the pressure still charge below an objectionable value. The pitch-laden oil is discharged into the separator 23 where a pressure substantially lower than that prevailing within the bulk supply drum 1 is maintained, the pressure being reduced by means of valve 24. Due to this reduction in pressure, the withdrawn pitch-laden oil is subjected to vaporization, the vapors entering the tower 27 and pitch components separating as a residue remaining unvaporized. The degree of vaporization can be controlled by regulating the pressure. As much as 80% or more of the pitch-laden oil may be so vaporized by its self-contained heat, but if a liquid residue is to be maintained it is usually not desirable to go much beyond this point and it may be necessary to reduce the amount of vaporization, although a liquid residue can sometimes be obtained with vaporization of as much as

90% of the pitch-laden oil. With still pressures in the neighborhood of 100 pounds per square inch or higher, the pressure in the separator 23 may be maintained at a value between atmospheric pressure and say 50 pounds per square inch or higher, depending upon the amount of vaporization desired, or the pressure in the separator 23 may be maintained at a value somewhat below atmospheric pressure. When the discharge of pitch-laden oil into the separator 23 is begun, and the vapors separated from this residual oil begin to pass through the tower 27, condensation in tower 27 is begun and the condensate is forced through the heating tubes 8. If the amount of such condensate is for any reason insufficient, additional raw oil may be supplied to the heating tubes 8 in admixture therewith through connection 37. Such raw oil may also be introduced into the reflux tower through connection 33 to assist in promoting condensation therein. The introduction of a part of the distillate product, or such raw oil, or other refluxing medium into the reflux tower 27 through connection 33 is regulated to effect condensation of those heavier and higher boiling components of the vapors suitable for further cracking. Operating for the production of gasoline, or gasoline-containing pressure distillates, with a gas oil character charging stock, with a still pressure in the neighborhood of 125 pounds per square inch, the temperature at the top of reflux tower 14 may be maintained in the neighborhood of 500° to 550° F. and the temperature at the top of the reflux tower 27 in the neighborhood of 350° to 400° F. Distillate may be taken off through connection 18 at a rate, for example, in the neighborhood of 1,000 gallons per hour, pitch-laden residual oil discharged from the bulk supply drum 1 to the separator 23 at a rate in the neighborhood of 1,500 gallons per hour, and raw oil supplied at a rate sufficient to maintain the still charge. Raw oil in excess of that required to maintain the desired temperature at the top of the reflux towers may be introduced, for example, through connection 40, or through connection 37. The invention has several important advantages. It provides important heat economies particularly in connection with operations of the type described in said Letters Patent No. 1,598,136. It provides for increased continuity of operation without sacrifice of efficiency. It affords close control of the cracking operation, and likewise provides desirable flexibility. It also provides for improved protection of the heating tubes of the still; the heating tubes through which unvaporized oil is recirculated are protected by tempering of the heating gases by heat absorption in the auxiliary heating tubes 130

and unvaporized oil is not recirculated through these auxiliary heating tubes. At the same time, the invention provides for advantageous treatment of the several types 5 of stocks circulating in the pressure still system. The relatively refractory condensate from the vapors separated under reduced pressure from the residual oil discharged from the pressure still proper is 10 subjected to the most severe cracking conditions. Raw oils of more refractory character may also be supplied first to these auxiliary heating tubes while raw oil of less refractory character is supplied directly to 15 the pressure still proper.

We claim:

1. An improved method of cracking hydrocarbon oils, which comprises maintaining a body of oil in a vaporizing zone under a 20 superatmospheric pressure and heating it to a cracking temperature by circulating oil therefrom through heating tubes and back thereto, taking off vapors including vapors of the cracked product therefrom under pressure, discharging oil from the said body into a separate vaporizing zone maintained under a pressure lower than that prevailing in the first and taking off vapors from the second vaporizing zone, subjecting the vapors from 25 the second vaporizing zone to a condensing operation and forcing condensate from this condensing operation through separate heating tubes into the first vaporizing zone, and passing heating gases from a firebox in 30 which fuel is burned for supplying heat to the cracking operation first over the heating tubes through which condensate from the said condensing operation is forced and then over the heating tubes through which oil 35 from the said body is circulated.

2. An improved method of cracking hydrocarbon oils, which comprises maintaining a body of oil in a vaporizing zone under a superatmospheric pressure and at a cracking 45 temperature and taking off vapors including vapors of the cracked product therefrom under pressure, forcing oil into the said vaporizing zone through heating tubes and heating it to a cracking temperature therein, discharging oil from the said body into a separate vaporizing zone maintained under a pressure lower than that prevailing in the first and taking off vapors from the second vaporizing zone, subjecting the vapors from 50 the second vaporizing zone to a condensing operation and forcing condensate from this condensing operation through separate heating tubes into the first vaporizing zone, and passing heating gases from a firebox in 55 which fuel is burned for supplying heat to the cracking operation first over the heating tubes through which condensate from the said condensing operation is forced and then over the first mentioned heating tubes.

3. An improved method of cracking hy-

drocarbon oils, which comprises maintaining a body of oil in a vaporizing zone under a superatmospheric pressure and at a cracking temperature, taking off vapors including vapors of the cracked product therefrom 70 under pressure and subjecting these vapors to a refluxing operation, forcing oil including reflux condensate from the said refluxing operation into the said vaporizing zone through heating tubes and heating it to a cracking temperature therein, discharging oil from the said body into a separate vaporizing zone maintained under a pressure lower than that prevailing in the first and taking off vapors from the second vaporizing zone, 75 subjecting the vapors from the second vaporizing zone to a condensing operation and forcing condensate from this condensing operation through separate heating tubes into the first vaporizing zone, and passing heating gases from a firebox in which fuel is burned for supplying heat to the cracking operation first over the heating tubes through which condensate from the said condensing operation is forced and then over the first mentioned heating tubes.

4. An improved method of cracking hydrocarbons oils, which comprises maintaining a body of oil in a vaporizing zone under a superatmospheric pressure and at a cracking 95 temperature, taking off vapors including vapors of the cracked product therefrom under pressure and subjecting these vapors to a refluxing operation, introducing raw oil into the vapors in this refluxing operation, forcing oil including admixed reflux condensate and unvaporized raw oil from this refluxing operation into the said vaporizing zone through heating tubes and heating it to a cracking temperature therein, discharging oil from the said body into a separate vaporizing zone maintained under a pressure lower than that prevailing in the first and taking off vapors from the second vaporizing zone, subjecting the vapors from the second vaporizing zone to a condensing operation and forcing condensate from this condensing operation through separate heating tubes into the first vaporizing zone, and passing heating gases from a firebox in which fuel is burned for supplying heat to the cracking operation first over the heating tubes through which condensate from the said condensing operation is forced and then over the first mentioned heating tubes.

5. An improved method of cracking hydrocarbon oils, which comprises maintaining a body of oil in a vaporizing zone under a superatmospheric pressure and at a cracking temperature and taking off vapors including vapors of the cracked product therefrom under pressure, forcing oil into the said vaporizing zone through heating tubes and heating it to a cracking 125 temperature therein, discharging oil from

- the said body into a separate externally unheated vaporizing zone maintained under a pressure lower than that prevailing in the first and taking off vapors from the second 5 vaporizing zone, subjecting the vapors from the second vaporizing zone to a condensing operation and forcing condensate from this condensing operation through separate heating tubes into the first vaporizing zone, 10 and passing heating gases from a fire-box in which fuel is burned for supplying heat to the cracking operation first over the heating tubes through which condensate from the said condensing operation is forced and 15 then over the first mentioned heating tubes.
6. An improved method of cracking hydrocarbon oils, which comprises maintaining an externally unheated body of oil in a vaporizing zone under a superatmospheric 20 pressure and at a cracking temperature and taking off vapors including vapors of the cracked product therefrom under pressure, forcing oil into the said vaporizing zone through heating tubes and heating 25 it to a cracking temperature therein, discharging oil from the said body into a separate externally unheated vaporizing zone maintained under a pressure lower than that prevailing in the first and taking off 30 vapors from the second vaporizing zone, subjecting the vapors from the second vaporizing zone to a condensing operation and forcing condensate from this condensing operation through separate heating 35 tubes into the first vaporizing zone, and passing heating gases from a firebox in which fuel is burned for supplying heat to the cracking operation first over the heating tubes through which condensate from the 40 said condensing operation is forced and then over the first mentioned heating tubes.
7. An improved method of cracking hydrocarbon oils, which comprises maintaining a body of oil in a vaporizing zone 45 under a superatmospheric pressure and heating it to a cracking temperature by circulating oil therefrom through heating tubes and back thereto, taking off vapors including vapors of the cracked product therefrom under pressure and subjecting these 50 vapors to a refluxing operation, returning reflux condensate therefrom to the said body of oil and separately condensing vapors remaining uncondensed therein, discharging oil from the said body into a 55 separate vaporizing zone maintained under a pressure lower than that prevailing in the first and taking off vapors from the second vaporizing zone, subjecting the vapors from the second vaporizing zone to a separate refluxing operation and forcing reflux condensate therefrom through separate heating tubes into the first vaporizing zone, separately condensing vapors remaining uncondensed 60 therein, and passing heating gases from a

firebox in which fuel is burned for supplying heat to the cracking operation first over the heating tubes through which condensate from the said condensing operation is forced and then over the heating tubes 70 through which oil from the said body is circulated.

8. An improved apparatus for cracking oil, comprising a heating furnace having a heating flue and a firebox connected to one end of the heating flue, a bulk supply drum and a battery of heating tubes arranged in the said heating flue and circulating connections for circulating oil from the bulk supply drum through the heating tubes and 75 back to the bulk supply drum, means for taking off vapors from the bulk supply drum under pressure, a separator and connections including pressure reducing means between a point in the bulk supply drum below the normal liquid level therein and the separator, a vapor outlet from the said separator, condensing means and connections between the vapor outlet from the separator and the said condensing means, a separate bank of heating tubes arranged in the said heating flue between the firebox and the first mentioned heating tubes, connections between 80 one end of this bank of heating tubes and the bulk supply drum, and connections including a forcing means for supplying condensate from the said condensing means to the other end of the said separate bank of heating tubes.

9. An improved apparatus for cracking oil, comprising a heating furnace having a heating flue and a firebox connected to one end of the heating flue, a vapor separating chamber, means for taking off vapors therefrom under pressure, heating tubes arranged in the said heating flue and discharge connections therefrom to the said vapor separating chamber, connections including a forcing means for circulating oil through the said heating tubes into the said vapor separating chamber, a second vapor separating chamber, connections including pressure reducing means between a point in the first said vapor separating chamber below the normal liquid level therein and the second said vapor separating chamber, condensing means and a vapor connection between the second said vapor separating chamber and this condensing means, separate heating tubes arranged in the said heating flue between the firebox and the first mentioned heating tubes and discharge connections therefrom to the first said vapor separating chamber, and connections including a forcing means for circulating condensate from the said condensing means through the said separate heating tubes into the first said vapor separating chamber.

10. An improved apparatus for cracking oil, comprising a heating furnace having a

- heating flue and a firebox connected to one end of the heating flue, an externally unheated vapor separating chamber, means for taking off vapors therefrom under pressure,
5 heating tubes arranged in the said heating flue and discharge connections therefrom to the said vapor separating chamber, connections including a forcing means for circulating oil through the said heating tubes into
10 the said vapor separating chamber, a second externally unheated vapor separating chamber, connections including pressure reducing means between a point in the first said vapor separating chamber below the normal liquid
15 level therein and the second said vapor separating chamber, condensing means and a vapor connection between the second said vapor separating chamber and this condensing means, separate heating tubes arranged in the said heating flue between the firebox 20 and the first mentioned heating tubes and discharge connections therefrom to the first said vapor separating chamber, and connections including a forcing means for circulating condensate from the said condensing 25 means through the said separate heating tubes into the first said vapor separating chamber.
